PAPER TOWEL DISPENSING APPARATUS

Frank G. Steiner, Chicago, Ill., assignor to Steiner Sales Company, Salt Lake City, Utah, a corporation of Utah

Application April 26, 1935, Serial No. 18,397

3 Claims. (Cl. 312—53)

This invention relates to a mechanism for dispensing paper towels of the inter-folded type wherein the pulling out of one towel pulls the end of the next towel into an accessible position.

5 The invention includes features, some of which are applicable for the dispensing of other kinds or types of paper toweling.

The preferred embodiment of the invention shown herein includes means for preventing 10 quick successive operations of the feeding mechanism, thus making it necessary for the user to wait for some predetermined time period before he can obtain a second towel. By this means, the 15 number of towels used is substantially reduced and great economic gain is made.

Features of the invention include: the down-feed and delivery of the towels for access from the bottom of the cabinet; the incorporation of friction-reducing means in the towel supply support; the arrangement of the feed-roll-separating and stop mechanism; and the details of construction of the same and the broader ideas of means inherent in the disclosure.

Objects, features and advantages of the invention will be set forth in the description of the drawings forming a part of this application, and in said drawings:

Figure 1 is a front sectional elevation viewing the mechanism as when the door is removed 30 and with the timer and stop mechanism positioned as in Figure 5;

Figure 2 is a vertical transverse section on line 2—2 of Figure 1;

Figure 3 is a view similar to Figure 2 with the 35 mechanism positioned as after a feeding operation, and with a towel so positioned as to be accessible to the user, and with the timer and stop mechanism positioned as in Figure 4;

Figure 4 is a vertical transverse section on line 40 4—4 of Figure 1, showing the timer stop mechanism positioned as immediately after towel delivery and withdrawal;

Figure 5 shows in full lines the timing and stop mechanism positioned as at the end of the 45 timing period, and shows, in dot-and-dash lines, the position of the stop arm and timer control link as during the feeding operation;

Figure 6 is a plan section on line 6—6 of Figure 1, with the parts positioned as in Figure 4;

50 Figure 7 is a vertical section on line 7—7 of Figure 6 showing the means acting promptly after feeding to prevent reverse motion of the feeding means; and

Figure 8 is a section similar to Figure 7 but 55 showing the stop arm and its pawl positioned as

just before the pawl assumes the position of Figure 7:

The drawings show the, at present, preferred embodiment of the invention, but the invention is not entirely limited to the details shown.

In the drawings, numeral 1 indicates the casing or cabinet which has a door 2 hinged at its bottom, as at 3, to the bottom of the casing. A suitable lock is shown at 4. Within the cabinet are arranged two plates respectively indicated 10—11, said plates being spaced from the end walls of the cabinet and being suitably secured as at 12—13 to the walls of the cabinet. The back wall 14 has inverted keyhole slots 15 adapted to be engaged with hooks on the wall to support the cabinet. 15

The towel supply chamber is defined by the plates 10—11, the rear wall 14, the door 2 and a pair of plates, see Figures 2 and 6, the members of which are respectively generally indicated at 18—19. These plates form the bottom of the towel supply chamber, and the pile of towels is supported upon them. Each plate has a flat portion 20 provided with a plurality of transverse, spaced, relatively narrow, upwardly bulging portions 21. The plate is bent downwardly as at 22, then upwardly curved as at 23 and then is bent to provide a horizontal portion 24, spaced below the portion 23. The plate is then bent upon itself to provide a smooth rounded portion 25, is then arched outwardly as at 26, and ends in a relatively flat, inwardly directed portion 27, the lower longitudinal edge of which is slightly spaced from the periphery of one of the feed rolls. These plates have down-turned flanges which are 30 suitably secured to the plates 10 and 11 by means generally indicated at 30. 35

The plates 18 and 19 are substantially identical in configuration but are arranged as rights and lefts, with their portions 25 and 27 spaced to provide a downwardly leading throat delivering to the feed rolls. The bottom-most sheets of the supply of paper rest on the apices of the elements 21 and 23, and have, so to speak, a bridging relation with these elements. Inasmuch as 45 there are only line contacts between the elements 21 and 23 and the paper, withdrawal friction is reduced to the minimum. For clearness, the lowermost sheets have been differentiated by making one solid black, defining others by two 50 lines only, and others by two lines, plus stippling.

The rounded portions 25 are spaced from one another at each side of a vertical mid-line passing between the rolls, and the rolls are respec- 55

tively indicated at 31—32. Referring to Figure 1: Roll 31 has a shaft 33 which is journaled in and passes laterally beyond the side plates 10 and 11. One end of this shaft extends through the outer 5 wall of the casing and has attached thereto a suitable operating crank 35. The roll 32 has a shaft 36 which is journaled in horizontal slots 37 of the plates 10 and 11. By this arrangement, the roll 32 can move toward and away from the 10 roll 31, that is to feeding and non-feeding positions. Normally, the bottom-most portion 40 of the sheet lies between the spaced rolls as shown in Figure 2 so that when the rolls are brought together and rotated, this portion 40 is brought to 15 the accessible position shown in Figure 3 while a corresponding portion 41 of the next sheet is brought to the position shown in Figure 3 in a position to be fed by a subsequent operation of the feed rolls. It is, of course, understood that 20 as one sheet is fed outwardly, another sheet is drawn to feeding position.

Below the rolls is a throat into and through which the fed towel is delivered. This throat is formed by a pair of spaced plates 28 leading to 25 an opening 29 in the bottom wall of the casing. A feature of the invention is the downward delivery of the sheets to a point outside of and below the cabinet for access by the user. The throat-forming plates are held by suitable fastening means to the plates 10 and 11 and, of course, extend from one plate to the other.

An important feature of the invention is the construction of the combined stop and feed roll control mechanism now to be described. Referring first to Figures 6, 7 and 8: The shaft 33 is provided at opposite ends with arms respectively designated 43 and 44 adapted to engage the shaft 36 of the roll 32 and move it in the slots away from the friction surface 45 of the roll 31, and to 40 temporarily releasably lock the roll 31 against further motion, as well as to hold the roll 32 in non-feeding position. Each arm 43 and 44, therefore, has in its periphery a depression or notch 46, see Figure 8, adapted to receive the shaft 45 36, as shown in Figures 4, 5, 6 and 7. The shaft 36 is urged toward the roll 31 by means of springs, one at each end of the shaft, and attached as at 46 to the plates 10 and 11. One arm of each spring engages a stop 48, and the other arm passes 50 through an opening in a clip 50 circumscribing the shaft 36. The spring, of course, is coiled, as shown in Figure 6, at 51 and tends to press the shaft 36 toward the roll 31. The clip 50 is slotted as at 52, so that the arms 43 and 44 can directly 55 engage the ends of shaft 36.

Referring to Figure 7: In order to prevent reverse rotation of the rolls at the end of each feeding operation, a pawl 55 is provided and is arranged as shown in Figures 7 and 8, and pivoted 60 at 56 to the plate 11. In Figure 7, the pawl is positioned to prevent rotation of the arm 43 in a direction opposite to that of the arrow. In Figure 8, the pawl is being pushed by the arm to a position from which it will swing to the position 65 of Figure 7. Figure 7 shows the separated non-feeding position of the rolls, and Figure 8 shows the rolls in feeding position but just about to be moved from feeding position as the arm 43 swings to bring its notch 46 in releasably locked engagement with the shaft 36. Each arm 43—44 has a cam surface 58 which leads to the depression or notch 46 and gradually pushes the shaft 36 outwardly to its non-feeding position.

The arrangement of a stop arm, now to be 75 described, on the shaft 33, adjacent one of the

arms, arm 44 for example, is also a feature of this invention. The mechanism includes a small stop arm 60, see Figures 1, 4, 5 and 6, having pivoted thereto as at 61, a link 62 slotted as at 63. Through the slot slidably passes a pin or projection 64 of a connection 65. This connection is slidably held at its upper and lower portions in brackets respectively indicated 66—67. The connection has a laterally bent portion 70 providing clearance for the arm 60 only at the end of a 10 timing operation, see Figure 5, and said connection at its upper end has spaced lateral extensions 71 engaged with a head 72 of a piston stem 73 of a piston timer 74. The inner construction of this timer is not shown. It will be understood, however, that when the piston is pushed to the position shown in Figure 4, it automatically travels downwardly at a regulated rate to the position shown in Figure 5, thus performing the timing operation. There is no intention to be limited to 15 the kind of timer.

When the parts are positioned as in Figure 4, the stop arm 60 is so related to the vertical portion 75 of the link that the shaft 33 cannot be turned in the direction of the arrow because the 20 stop arm immediately engages the part 75. At the end of the timing period, the off-set portion 70 of the connection is brought into opposition to the part 60 so that the latter is free to make a complete revolution in counter-clockwise direction from the position shown in Figure 5, again to that position thus permitting a feeding operation, which is accomplished herein by a single rotation of the shaft 33. During this operation, the roll 32 moves to feeding position, is operated 30 for feeding and is moved again to its spaced non-feeding position.

Operation

Assume the parts of the machine to be positioned as shown in Figures 2 and 5. On rotation 40 of the shaft by means of the crank 35 in counter-clockwise direction, as viewed in Figure 5, the arm 60 is moved and the link 62 is drawn upwardly correspondingly moving the connection 65 upwardly. The full upward movement of the connection to set the timer is made at about the end of a half revolution of the shaft 33, that is when the parts assume the dot-and-dash line position shown in Figure 5. On completion of the feeding 50 rotation of the shaft to the position shown in Figure 4, the link assumes the position shown in that figure and the timer is thus free to act and move downwardly merely swinging the link in clockwise direction. With the parts positioned as 55 in Figure 4, the shaft cannot be turned because of the relation of the stop 60 to the part 75 of the connection 65. At the end of the timing period, however, as shown in Figure 5, the stop arm is free to rotate because the off-set portion 70 is 60 opposed to it. On slight initial movement of the shaft 33 from the position in Figure 5, the arms 43, 44 move to release the roll 32, which immediately moves to feeding position so that feeding occurs while the shaft 33 continues its motion. 65 It will, of course, be understood that each time a towel is moved to position for access by the user, it pulls the end of the next towel between the rolls in position to be fed at the next operation of the machine.

There is no intention to be entirely limited to the use of any particular number of feed rolls, nor indeed to the use of rolls at all, because other modes of feeding might be employed. I believe myself the first to separately and successively 70

deliver ready-cut sheets of paper toweling from a stack, bundle, pile or assembly, in combination with means for delaying delivery of a second towel for a predetermined time interval, by the 5 use of a timer.

I claim as my invention:

1. A mechanism for dispensing paper towels of the inter-folded type including first and second feed rolls and shafts therefor, between which rolls 10 the end of the bottom-most sheet of a pile of inter-folded towels normally lies and between which the end of the following towel is pulled when the forward towel is withdrawn, means yieldably holding the second roll against the 15 first, a pair of arms one on each end of the shaft of the first roll and engageable with the shaft of the second roll to move the second roll away from the first and releasably hold it in non-feeding position, a stop mechanism including a 20 stop arm also carried by the shaft of the first roll, said stop arm and pair of holding arms being so related that the holding arms assume holding position by the time the stop arm reaches stop position.
- 25 2. A mechanism for dispensing towels having feeding means including a roll, a stop mechanism controlling and controlled by the roll, including a stop arm controlled by the roll, timer means, which is set and thereafter automatically per- 30 forms its timing function, a setting connection

for the timer means having a portion which is moved as a stop into the path of the stop arm when the timer is set, a link and means connecting it with said stop arm and setting connection so that it controls said connection to set the timer 5 and thereafter release the connection for independent movement under control of the timer, said connection having an offset portion into and out of which said stop arm can move at the end of the timing operation, to again permit operation of the roll.

3. A mechanism for dispensing paper including a measuring roll, and a pinch roll therefor, journaled to be moved away from the measuring roll to release the paper for withdrawal, means 15 yieldably holding the pinch roll against the measuring roll, a stop mechanism controlled by and controlling the measuring roll including a stop arm on the measuring roll, and means also on the measuring roll for moving the pinch roll away 20 from the measuring roll and for releasably holding the same, including arms which engage the journaling elements of said pinch roll, said arms being so angularly related to the stop arm as to cause the pinch roll to be moved away from the 25 measuring roll as the stop arm approaches stop position and to be so held while the stop arm remains at stop position.

FRANK G. STEINER. 30
